John B. Cataldo, Birmingham, Mich., assignor, by mesne assignments, to I-T-E Circuit Breaker Company, Philadelphia, Pa., a corporation of Pennsylvania

Application May 28, 1956, Serial No. 41,673

Term of patent 14 years

(Cl. D26—5)

FIG. 5

Figure 1 is a front elevational view of an electrical duct fitting, showing my new design;

Figure 2 is a side elevational view, the opposite side having substantially the same appearance;

Figure 3 is a top plan view;

Figure 4 is a bottom plan view; and

Figure 5 is a perspective view thereof.

The dominant features of my new design are shown in solid lines in the drawing.

I claim:

The ornamental design for an electrical duct fitting, as shown and described.
